UNITED STATES PATENT OFFICE

153,543

DESIGN FOR A SIGNAL LAMP

Ora E. Oyler, Rosemead, Calif.

Application April 13, 1948, Serial No. 145,673

Term of patent 7 years

(Cl. D48—32)

To all whom it may concern:

Be it known that I, Ora E. Oyler, a citizen of the United States, residing at Rosemead, in the county of Los Angeles and State of California, have invented a new, original, and ornamental Design for a Signal Lamp, of which the following is a specification, reference being had to the accompanying drawing, forming part thereof.

Figure 1 is an elevational view of a signal lamp, showing my new design;

Figure 2 is a top plan view thereof, and

Figure 3 is an end view of the same.

I claim:

The ornamental design for a signal lamp, as shown.

ORA E. OYLER.
